UNITED STATES PATENT OFFICE.

JAMES ZEDRICK ELDER, OF KILGORE, TEXAS, ASSIGNOR OF ONE-HALF TO CHARLES R. FLOUREY, OF KILGORE, TEXAS.

COLTER.

1,180,580.

Specification of Letters Patent. Patented Apr. 25, 1916.

Application filed August 3, 1915. Serial No. 43,497.

To all whom it may concern:

Be it known that I, JAMES ZEDRICK ELDER, a citizen of the United States, residing at Kilgore, in the county of Gregg and State 5 of Texas, have invented a new and useful Colter, of which the following is a specification.

This invention relates to an improvement in colters, and the object is in the appropriation of means for fastening the colter to the mold board and in the mounting of 10 the colter upon the mold board and share.

The invention consists of certain novel features of construction and combination of 15 parts, which will be hereinafter described and pointed out in the claims.

Many slight changes may be made in the form and arrangement of the several parts described, without departing from the spirit 20 and scope of the invention, and hence I do not wish to be limited to the exact construction as herein set forth.

In the accompanying drawings, Figure 1 is a perspective view of a plow showing 25 the invention applied thereto. Fig. 2 is a view in side elevation. Fig. 3 is a transverse vertical sectional view. Fig. 4 is a perspective view of the colter. Fig. 5 is a perspective view showing the modified form 30 of colter applied to a plow. Fig. 6 is a horizontal sectional view through the standard and colter showing the manner of mounting the colter.

A represents the standard or post of the 35 plow and B is the land-side connected thereto. A mold board C is connected to the post or standard and is supported upon a flange 1 formed on the standard. Bolts 2 connect the mold board to the flange 1 and nuts 40 3 are screwed upon the bolts 2 for maintaining the mold board in position.

A share or point 4 is connected to the lower terminal of the mold board. A colter consisting of a vertical blade 6 is mounted 45 upon the mold board and share along the edge thereof or the ridge of the plow which is beveled on one side thereof, as at 7, for forming a cutting edge for the purpose of cutting the sod. A lip or wing 8 is connected to the blade 6 and extends at an 50 angle therefrom, conforming to the contour of the mold board C. The wing or lip 8 is provided with openings which register with the openings of the mold board, and

the bolts 2 which fasten the mold board to 55 the standard are passed through the openings of the wing for fastening the wing, mold board and standard together, and maintaining the blade rigidly in position and along the ridge of the plow so that one 60 surface of the blade is in the same vertical plane with the land-side B.

The blade extends downwardly to the point or share 4, but does not project the full length of the share. The cutting edge 65 of the blade is preferably held at an incline when the colter has been applied to the mold-board.

The wing 8 is bent at an angle from the lower side of the blade 6, and is mounted on 70 the mold-board, but extends short of the share, that is, the wing does not extend beyond the lower edge of the mold-board, so that it will not interfere with the removal of the point or share at any time, for the purpose 75 of renewing the point or share.

A notch or recess 9 is formed on the lower side of the blade 6 and above the upper edge of the wing 8, so that in the application of the colter blade to the mold-board 80 the notch will receive the upper edge of the mold-board, and the lower side of the upper portion of the blade 6 will rest against the post A.

In the construction set forth in Figs. 5 and 85 6 the blade 6 is provided with a wing 10 which is provided with an opening 11 for the reception of a bolt 12, which fastens the mold-board C to the standard A. Connected to the upper terminal of the blade 6 is a yoke 90 consisting of arms 13 which receive the standard A therebetween. A plate 14 is placed upon the arms, which is brought into engagement with the standard A and the plate is held in position by nuts 15, which are 95 screwed upon the terminals of the arms for fastening the upper terminal of the colter to the standard.

From the foregoing it will be seen that I have provided a colter which can be applied 100 to the mold-board of a plow by the bolts which connect the mold-board to the standard, and maintain the colter along the ridge of the plow so that the turf and sod can be readily cut in plowing.

105
What is claimed is:—

1. The combination with a plow standard, a mold board, and a fastening device pass-

ing through the mold board and standard to secure the same together, of a colter blade mounted on the mold board and having a wing lying flat against the mold board in 5 register with said fastening device and adapted to receive the device therethrough for securing the colter blade in place.

2. The combination with a plow standard, of a mold-board and plow share mounted on the standard, a colter blade mounted upon the mold-board and share along one edge thereof in line with the point of the plow, a wing on the blade resting against the mold-board, and securing means engaging 10 said wing and mold-board to hold the same upon the standard.

3. The combination with a plow standard, of a mold-board and plow share mounted on the standard, a colter blade mounted 20 on the mold-board and plow share along one edge thereof in line with the point of the plow, means on the blade engaging the mold board, and means connecting said means and mold-board to the standard, said blade 25 having a notch formed therein in which the upper edge of the mold-board is received and the upper terminal of the blade brought into engagement with the plow standard.

4. The combination with a plow standard, 30 of a mold-board and plow share mounted on the standard, a colter blade mounted on the mold-board and plow share along one edge thereof in line with the point of the plow, a wing connected to the blade extending over 35 and upon the mold-board and short of the plow share, and means passing through and

connecting said wing and mold-board to the standard.

5. The combination with a plow standard, and a mold-board and plow share mounted 40 thereon, of a colter blade mounted upon the mold-board and share, the upper terminal of the blade being rigidly engaged with the standard above the mold-board, and the lower terminal of the blade extending over 45 the share, a wing projecting inwardly from the blade and mounted upon the mold-board, and a bolt and nut for connecting the wing to the mold-board and standard, whereby the blade is maintained rigidly in 50 position with its outer face in the same vertical plane as the landside.

6. The combination with a plow standard, and a mold-board and plow share mounted thereon, of a colter blade mounted upon the 55 mold-board and share, the lower terminal of the blade extending over the share, a wing projecting inwardly from the blade and mounted upon the mold-board, and a bolt and nut for connecting the wing to the mold- 60 board and standard, whereby the blade is maintained rigidly in position with its outer face in the same vertical plane as the landside.

In testimony, that I claim the foregoing 65 as my own, I have hereto affixed my signature in the presence of two witnesses.

JAMES ZEDRICK ELDER.
